INDOOR TELEVISION ANTENNA

Sheldon Rutter, Evanston, Ill., assignor to Channel Master Corporation, Ellenville, N. Y., a corporation of New York

Application October 27, 1953, Serial No. 27,352

Term of patent 14 years

(Cl. D26—14)

To all whom it may concern:

Be it known that I, Sheldon Rutter, a citizen of the United States, and a resident of Evanston, Illinois, have invented a new, original, and ornamental Design for an Indoor Television Antenna, of which the following is a specification, reference being had to the accompanying drawing forming a part hereof.

Figure 1 is a top plan view of an indoor television antenna showing my new design.

Figure 2 is a front elevational view of said design.

Figure 3 is a side elevational view of said design.

The rear surface of said antenna is substan-

tially plain with the perforations shown in Figure 2 appearing thereon.

I claim:

The ornamental design for an indoor television antenna, as shown and described.

SHELDON RUTTER.
